L. C. BAYLES ET AL

ROTATION AND FEED REGULATOR

Filed Dec. 30, 1922

UNITED STATES PATENT OFFICE.

LEWIS C. BAYLES AND FRED M. SLATER, OF EASTON, PENNSYLVANIA, ASSIGNEES
TO INGERSOLL-RAND COMPANY, OF JERSEY CITY, NEW JERSEY, A CORPORA-
TION OF NEW JERSEY.

ROTATION AND FEED REGULATOR.

Application filed December 30, 1922. Serial No. 609,829.

This invention relates to fluid actuated rock drills of the hammer type, but more particularly to a machine of this type having automatic rotation, as for instance, rifle 5 bar rotation for the drill steel, and a fluid actuated feeding element for feeding the machine forward.

The objects of the invention are to enable the air feeding element to be controlled and permit light air feed to be used 10 on starting a hole, while at the same time permitting the rotation to be stopped altogether.

Another object of the invention is to enable the feeding and rotation controlling mechanism to be controlled by a hand rotated device, so that the machine may be used without the possibility of operation of the controlling mechanism when desired.

Further objects of the invention will hereinafter appear and to all of these ends the invention is shown in the accompanying drawings, in one of its preferred forms, in which—

Figure 1 is a side elevation in longitudinal section of a stope drill, on the line 1—1 of Figure 2, looking in the direction of the arrows, and embodying the invention.

Figure 2 is a horizontal sectional view on the line 2—2 of Figure 1, looking in the direction of the arrows with the parts in locked position,

Figure 3 is a view similar to Figure 2 with the parts released, and

Figure 4 is a horizontal sectional view of Figure 2 on the line 4—4 looking in the direction of the arrows.

Referring to the drawings, the machine comprises the cylinder A having a reciprocating piston B adapted to impart blows of impact to the drill steel C, which extends into the front head D and rotating chuck E, in position to receive the blows of impact of the hammer piston. The piston is provided with a forward fluted extension E' passing through the front cylinder washer F and engaging flutes G on the chuck E. The rearward extension H of the piston engages the usual rifle bar J provided with the usual ratchet and pawl mechanism for causing rotation. The rifle bar head K is provided with the spring pressed pawls L adapted to engage the ratchet ring O located in the back cylinder extension P.

The head block Q carries the throttle valve R controlling the supply of motive fluid to the percussive element and to the air feeding element of the machine through the inlet S. Without describing the course and distribution of the motive fluid to the cylinder and piston, it will be sufficient to state that as the piston reciprocates under the action of motive fluid, rotation will be imparted to the steel.

The air feed cylinder T is provided with the piston U having the piston rod V and a pivoted foot piece W at the lower end of the piston rod is formed with the rock engaging points X. The cylinder T is in slidable but non-rotatable engagement with the piston rod V, due to the projections Y on the cylinder engaging grooves Z in the piston rod. The percussive element and the air feeding element of the machine are held together by the usual side rods a.

Motive fluid is constantly supplied to the air feed cylinder from the throttle R through the port b and a relief port c leads from the air feed cylinder to the valve chamber d of the valve e, which controls communication 80 between the relief port c and the atmospheric vent f.

The ratchet ring O of the rotation mechanism is in this instance provided with a finger g adapted to bear upon the head h of the valve e, and a spring j is shown compressed between the valve e and the cap k, in which cap a vent o is placed. The spring j is of insufficient strength to resist the tendency of the ratchet ring O to rotate when the machine is running, so that when the valve e is released and permitted to move in the valve chamber d, the rotation for the machine becomes slip rotation, or else the rotation is stopped altogether, and the piston B merely reciprocates without rotating, due to the fact that the ratchet ring O is not held tightly in the head block P.

A stop, in the form of a pin p, is mounted at the side of the valve e and provided with a spring q adapted to be compressed between the collar r on the stop pin and the plug s surrounding the stem of the pin. The pin p is provided with a projection t which is adapted to slide in the slot u in the cap or plug s so that the stop pin, which is controlled by the handle or finger piece v may be moved inwardly into

the path of the relief valve *e* beneath the head *h* as indicated in Figure 2, in order to lock the valve from movement or else the stop pin *p* may be withdrawn and rotated to permit the projection *t* to lie upon the top of the plug *s* thus releasing the release valve *e*.

In the operation of the device, let it be assumed that a hole *w* is to be started along the slanting face *w* of the rock, as indicated in Figure 1. Under such conditions it may be highly desirable to permit the percussive element to operate as required without rotating the drill steel and with light air feed in the air feed cylinder. If strong rotation is permitted, under such circumstances, difficulty is experienced in collaring the hole. By pulling out the stop pin *p* to the position indicated in Figure 3, the abutment afforded by the head *h* of the relief valve *e* against the finger *g* of the ratchet ring *O* is released, and the ratchet ring *O* is free to move back and forth as the piston *B* reciprocates, so that the rotation is not imparted to the drill steel. At the same time, the vent in the air feed cylinder is open through the passage *e* and atmospheric vent *f*, or is opened and closed intermittently as the finger *g* of the ratchet ring *O* presses the relief valve back and forth under the influence of the spring *j*. In order to again apply the full force of the air feed and restore the full rotation, the

stop pin *p* is again moved inwardly to catch under the head *h* of the relief valve *e* to lock the valve from movement, as indicated in Figure 2.

We claim:

In a fluid actuated rock drill of the hammer type, the combination of rifle bar rotation for the drill steel having a releasable ratchet ring adapted to be moved by resistance to rotation when released, means for feeding the machine forward, said means being constantly exposed to pressure fluid, a stop on the ratchet ring, a valve controlling the feeding means mounted adjacent the ratchet ring and adapted to be actuated by said stop, a spring tending to force said valve to closed position but of insufficient strength to resist rotation of the ratchet ring, a spring pressed valve stop to positively engage the valve for normally holding the valve and the ratchet ring immovable, and a finger piece on the stop whereby said stop may be withdrawn to release the valve and the ratchet ring for permitting free oscillation of the ratchet ring and reciprocation of the valve and to permit a portion of pressure fluid to be intermittently released from the feeding means by the valve.

In testimony whereof we have signed this specification.

LEWIS C. BAYLES.
FRED M. SLATER.
